UNITED STATES PATENT OFFICE

LOUIS PUTNAM COOK, OF CLARENDON, NEW YORK.

WAGON-RACK STANDARD.

No. 895,344.

Specification of Letters Patent.

Patented Aug. 4, 1908.

Application filed July 26, 1907. Serial No. 385,711.

To all whom it may concern:

Be it known that I, LOUIS PUTNAM COOK, a citizen of the United States, residing at Clarendon, in the county of Orleans and 5 State of New York, have invented a new and useful Wagon-Rack Standard, of which the following is a specification.

This invention has relation to standards for wagon racks and it consists in the novel 10 construction and arrangement of its parts as hereinafter shown and described.

The object of the invention is to provide a standard of the character indicated which is of simple and durable construction and the 15 parts of which may be readily adjusted so that the wagon rack may be advantageously utilized for transporting hay, wood, stock or other material.

The standard consists primarily of a 20 hanger which is adapted to engage the side of a wagon body and is provided at its outer side with a flange having a curved slot cut therein. Binate arms are pivoted to the upper end of the hanger and are spaced 25 apart. Braces are pivoted at their upper ends to the arms and at their lower ends are provided with a pin which operates in the curved slot of the hanger.

In the accompanying drawing:—Figure 1 30 is a side elevation of the standard with the arms thereof lowered. Fig. 2 is an edge elevation of the standard in the position shown in Fig. 1, and Fig. 3 is a side elevation of the standard showing the arms elevated.

The standard consists of the hanger 1 35 which is provided at its upper end with a hook 2 which is adapted to be slipped over the upper edge of the side of a wagon body. The lower end of said hanger is provided with 40 a perforation 3 through which a pin, screw, nail or other securing device may be passed for the purpose of positively fixing the hanger with relation to the sides of the wagon body. The upper end of the hanger 1 is provided 45 with a lug 4 and the lower portion of the hanger 1 is provided at its outer side with an elongated flange 5 which is provided with a slot 6 which is outwardly curved at its upper end. The binate arms 7 are located one upon 50 each side of the lug 4 and are pivotally connected therewith. The said arms are spaced apart and the block 8 is interposed between

the outer ends thereof. The space between the said arms is sufficient for the reception of bolts which form the side of a wagon rack 55 securing means and inasmuch as the said arms are spaced apart practically along their entire length the side bars of the wagon rack may be adjusted to form a closed or open sided rack as desired. The braces 9 are pivoted at their 60 upper ends to the arms 7 at a point substantially midway between the opposite ends thereof. The lower ends of the braces 9 are provided with a pin 10 which is located in and operates within the slot 6. At the lower end 65 of the said slot 6 the hanger 1 is provided with a lug 11 upon which the lower end of the brace 9 may rest when the arms 7 are held in inclined relation to the said hanger 1. When the arms 7 are swung into a vertical position 70 with relation to the hanger 1 the pin 10 passes up the slot 6 and enters the outwardly curved upper end thereof, whereby, the braces 9 are swung in a lateral direction sufficiently to clear the lug 4, and form a means 75 for supporting the arms 7 in the said vertical position.

Having described my invention what I 80 claim as new and desire to secure by Letters-Patent is:—

A wagon rack standard comprising a hanger having a lug at its lower end portion, binate arms spaced apart along their entire length and pivoted to opposite sides of the hanger, the space between the arms being 85 adapted to adjustably receive the securing bolts of the side boards of the wagon rack, said hanger having at its lower portion an elongated slot located above said lug, braces pivotally connected at their outer ends with 90 the outer sides of the binate arms and a pin connecting the inner ends of the braces together, said pin being located in said slot said braces being chamfered at their ends and adapted to bear directly against the arms 95 and said lug when the arms are at an angle to the hanger.

In testimony that I claim the foregoing as my own, I have hereto affixed my signature in the presence of two witnesses.

LOUIS PUTNAM COOK.
